UNITED STATES PATENT OFFICE

CHARLES L'ENFANT, OF NEW YORK, N. Y.

ARTICLE HOLDER

Application filed November 13, 1929. Serial No. 406,765.

This invention relates to article holders, and has for its primary object and purpose to provide a simply constructed and serviceable device formed of flexible materials whereby a large number of keys or other rigid articles may be conveniently held or carried for ready access in segregated relation to each other, and in which the holder or case, when folded will present a comparatively flat non-bulky appearance so that it may be conveniently carried in the pocket or purse.

It is a more particular object of my invention, in certain practical embodiments thereof to provide in combination with the main flexible body wall of the case or holder, a single sheet of flexible material so formed and secured upon one side of said body wall as to cooperate with the opposite end portions of said wall to form article holding pockets.

It is another important feature of this embodiment of my invention to provide said additional flexible material with suitably located openings therein each associated with aligned pockets on the opposite ends of the case and through which the article contained in either of said pockets may be projected and positioned exteriorly of the pocket in position for use.

In another embodiment of the invention, I may provide a separate sheet of flexible material secured to the body wall of the case and associated with each of the end portions thereof to form a series of article receiving pockets together with one or more additional leaves each having a series of article receiving pockets and said leaves hingedly or flexibly secured to the intermediate portion of the body wall of the case between the first named spaced series of pockets thereon.

With the above and other objects in view, the invention consists in the improved article holder and in the form, construction and

relative arrangement of its several parts as will be hereinafter more fully described, illustrated in the accompanying drawings, and subsequently incorporated in the subjoined claims.

In the drawings, wherein I have disclosed several simple and practical embodiments of the invention, and in which similar reference characters designate corresponding parts throughout the several views,—

Figure 1 is an interior face view of an article holder or case constructed in accordance with one embodiment of my present improvements;

Fig. 2 is a sectional view taken on the line 2—2 of Fig. 1;

Figs. 3 and 4 are plan views of the blank parts from which the case is constructed;

Fig. 5 is a view similar to Fig. 1 showing a modified form of the device;

Fig. 6 is a sectional view taken on the line 6—6 of Fig. 5;

Fig. 7 is an interior face view showing another alternative form of the invention, parts thereof being broken away;

Fig. 8 is a sectional view taken on the line 8—8 of Fig. 7;

Fig. 9 is an interior face view illustrating another embodiment of the invention and parts thereof being broken away;

Fig. 10 is a sectional view taken on the line 10—10 of Fig. 9, and

Figs. 11 and 12 are views similar to Figs. 9 and 10, Fig. 12 being a section taken on the line 12—12 of Fig. 11 and showing still another form of the device.

In the construction of my improved article holder or case as shown in Figs. 1 to 4 inclusive, the device consists of the body wall 5 in the form of a sheet of leather or other suitable flexible material. This leather sheet is cut or stamped out into the blank form of suitable dimensions shown in Fig. 3 of the drawings, and includes intermediate and end sections 6 and 7 respectively, adapted to

be folded relative to each other along the horizontal lines indicated at 8 and 9. The intermediate sections 6 of the blank are of somewhat greater width than the end sections thereof to provide the narrow strips or flanges 10 along each of the lateral edges of the sections 6 which are adapted to be folded inwardly along the lines 11 to overlie the edges of parts positioned upon the intermediate sections 6 and be permanently secured thereto as will be presently explained.

The other part of the case or holder also consists of a sheet of flexible material 12 shown in its blank form in Fig. 4 of the drawings, the said sheet of material having a width approximate to the width of the sections 6 of the body wall 5 between the fold lines 11. The sheet 12 is however, relatively short, and is provided at its opposite ends 20 with spaced tabs or extensions 13. In line with the corresponding tabs at opposite ends of the sheet 12 and centrally of said sheet, a horizontally elongated opening 14 is formed therethrough.

In assembling the parts of the case as above described, the flexible sheet 12 is arranged upon the inner side of the body wall 5 and with the slots or openings 14 bisected by the center fold line 8 of the body wall. The end sections 7 of the body wall 5 are then turned inwardly and downwardly so that they overlie and substantially entirely cover the flaps or extensions 13 at the ends of the sheet 12, the marginal strips or flanges 10 of the body wall are then turned inwardly and downwardly upon the lateral edges of the end sections 7 of said wall and the sheet 12 and are permanently fixed or secured thereto by the lines of stitching indicated at 15. Also, a central longitudinal line of stitching 16 secures the sheet 12 and the end sections 7 to the intermediate sections 6 of the body wall, said latter line of stitching preferably terminating in spaced relation to the folds 9 at the opposite ends of the case. In addition, other lines of stitching indicated at 17 extend obliquely in opposite directions from points adjacent the ends of the openings 14 to the longitudinal lines of stitching 15 and 16 and further secure the sheet of material 12 to the body wall sections 6. In this manner, it will be readily understood from an inspection of Fig. 1 of the drawings, that there is produced upon one side of the body wall 5 two pairs of longitudinally aligned pockets, the inner ends of which gradually taper or decrease in width towards the openings 14.

In the form of the device as shown in the drawings, it is particularly designed as a holder or retainer for Yale keys. In inserting the individual keys into the several pockets of the case, the flap or extension 13 is first withdrawn from beneath the inner edge of the section 7 of the body wall 5, and the shank 45 of the key then inserted downwardly beneath

this flap and into the pocket until the key shank projects through one of the openings 14. The pocket is of sufficient width to permit the enlarged head of the key to readily move downwardly into the same as the shank is withdrawn through the opening 14. After the key head is disposed below the flap 13 and completely enclosed within the pocket, this flap is then again inserted beneath the edge of the body wall section 7 and the key shank 75 then forced inwardly through the opening 14 so as to position the head of the key in the outer end of the pocket, such movement being continued until the entire key is completely enclosed within the pocket. The case with the keys contained in the pockets thereof is adapted to be folded along the line 8 so that the two halves of the case are in face to face contact. The outer side of the body wall 5 of the case is entirely unobstructed and by making this body wall in various ornamental leathers, a highly attractive article of this kind may be produced. Since the individual keys are segregated from each other within the pockets, when the case is folded, the two series of keys will be at all times retained in flat superimposed relation. Thus the case will present a non-bulky appearance and may be conveniently carried in the vest pocket or the purse.

In Figs. 5 and 6 of the drawings, I show another embodiment of the device wherein the sheet of flexible material 12' secured to the inner side of the body wall is provided with the tab extensions 13 only at one of its ends and is secured to the body wall by spaced parallel lines of stitching 16' to form one series of key-receiving pockets. The end portion of the sheet 12 at one side of the series of openings 14 is slightly reduced in width so that its lateral edges are not secured by the in-turned marginal strips 10 of the body wall to provide a closure flap 18. The inwardly folded end portion 7' of the body wall, the lateral edge portions of which are secured beneath the inwardly turned marginal strips 10, in conjunction with said body wall, forms a coin purse or card holding pocket extending across the entire width of the case. This wall and the flap 18 are provided with the complementary elements of the conventional type of snap fastener indicated at 19 so that the flap 18 may be securely held in overlapping relation upon the body wall sections 7' to thus securely close the open side of the purse pocket.

In Figs. 7 and 8, I show another construction in which instead of providing the purse above referred to, one end of the flexible sheet 12^a extends substantially to one end edge of the body wall 5 which in this case is not provided at said end with an inwardly folded section. The free end edge and the lateral edges of this end part of the sheet 12^a remain free or unattached to the body wall. To the

inner side of this free end portion of the sheet 12^a a sheet of celluloid or other flexible transparent material indicated at 20 is secured along its opposite side edges by lines of stitching indicated at 20'. A similar sheet of celluloid 21 is also secured to the opposite lateral edges and the end edge of the body wall 5. There is thus provided upon the inner side of this end of the body wall and upon the 10 free end portion of the sheet 12^a two pockets having transparent walls or windows in which identification cards, automobile licenses or other documents may be conveniently carried.

15 In Figs. 9 and 10 of the drawings, I have shown another construction, in which a key pocket forming sheet of material 12^b is secured on the inner side of the body wall at each of its ends to cooperate with one of the 20 inwardly folded end sections 7 of said wall. Each sheet of material 12^b is folded upon itself and the folded parts thereof stitched along the parallel lines 16^b of the body wall to form the series of separate pockets, said 25 material having the opening 14^b cut therethrough at the inner end of each pocket. Thus, there is provided the two series of pockets, the inner opposed ends of which are spaced apart on opposite sides of the center 30 line of the foldable body wall of the case. In addition, I provide a third series of key receiving pockets consisting of a sheet of flexible material 22 folded on itself as at 23 in spaced relation to one of its ends. A second 35 flexible sheet of material 24 similar to the folded sheets 12^b is superimposed upon the folded end portion of the sheet 22.

The other end of the latter sheet is then 40 folded inwardly, and the several overlapping parts of these flexible sheets are stitched together to form the series of pockets. At the fold 23, the flexible sheet 22 is secured to the flexible body wall of the case between the two 45 series of pockets thereon formed by the sheets 12^b, by means of a horizontal line of stitching 25. Thus the sheets 22 and 23 forming the supplemental series of pockets provide a separate leaf capable of free flexing or hinging movement relative to the intermediate part 50 of the case. Notwithstanding this increase in the capacity of the case, when the two halves of the case are folded upon opposite sides of the intermediate leaf, the keys are very compactly arranged so that the case or 55 holder will not be excessively bulky.

In Figs. 11 and 12, I have illustrated the same construction in so far as the individual key receiving pockets are concerned, but provide the two separate swinging leaves attached to the intermediate part of the body wall of the case by the spaced parallel lines of stitching shown at 26. Thus the capacity 60 of the case is further increased.

From the foregoing description considered 65 in connection with the accompanying draw-

ings, the construction, several advantages and manner of use of my improved article holder will be clearly understood. It will be appreciated that in the form shown in Figs. 1 to 4 of the drawings, a very simple structure is presented, and one which may be manufactured on a quantity production basis at very small cost. Therefore, the article may be employed as an advertising medium by banks and other financial institutions, and be distributed gratis to renters of safety deposit vaults and other patrons. The other more elaborate constructions are also entirely practical and provide convenient and serviceable cases for compactly holding and retaining against loss of a large number of keys, while at the same time, the case construction permits of the easy accessibility to any one of a number of keys carried therein and will occupy but a minimum of space in the pocket or 80 purse.

While I have shown and described several desirable forms of my present improvements, it is nevertheless to be understood that the essential features thereof might also be incorporated in various other alternative structures, and I accordingly reserve the privilege of resorting to all such legitimate changes therein as may be fairly embodied within the spirit and scope of the invention as claimed. 95

I claim:

1. A case having a body wall of flexible material, the opposite end portions of said body wall being inwardly folded upon one side of said wall, and a separate sheet of material secured to said side of the body wall by spaced parallel lines of stitching and having opposite end portions thereof cooperating with said inwardly folded end portions of said body wall to constitute closure means for 100 pockets formed between said body wall and the inwardly folded end portions thereof.

2. A case having a body wall of flexible material, opposite end portions of said wall being inwardly folded upon one side thereof, a separate sheet of flexible material secured to said side of the body wall and extending between the terminal edges of said folded end portions of said wall to form in conjunction therewith longitudinally aligned pockets, and said sheet of flexible material at its approximate central portion having an opening therein communicating with the aligned pockets and through which an article contained in either pocket may be withdrawn. 110

3. A case having a body wall of flexible material, opposite end portions of said wall being inwardly folded upon one side thereof, a separate sheet of flexible material secured to said side of the body wall and extending between the terminal edges of said folded end portions of said wall to form in conjunction therewith longitudinally aligned pockets, and said sheet of flexible material at its approximate central portion having an opening 120

therein communicating with the aligned pockets and through which an article contained in either pocket may be withdrawn, and said sheet of flexible material at each of its ends having a tab extension to underlie the edge of one of the inwardly folded ends of the body wall and constitute closure means for said pockets.

5 In testimony that I claim the foregoing
10 as my invention, I have signed my name
hereto.

CHARLES L'ENFANT.
